The ornamental design for a tire tread for pneumatic tire, as shown and described.

DESCRIPTION

FIG. 1 is a perspective view of a tire tread for pneumatic tire showing our new design, it being understood that the tread pattern repeats circumferentially about the outer circumference and shoulder of the tire.

FIG. 2 is a left side elevational view, the right side elevational view being a mirror image thereof; and,

FIG. 3 is a front elevational view, the rear elevational view being a mirror image thereof.
